UNITED STATES PATENT OFFICE.

FERDINAND SCHTABE, OF BROOKLYN, NEW YORK.

LEVEL.

No. 903,011.

Specification of Letters Patent.

Patented Nov. 3, 1908.

Application filed October 28, 1907. Serial No. 399,581.

To all whom it may concern:

Be it known that I, FERDINAND SCHTABE, a citizen of the United States, residing at Brooklyn, in the county of Kings and State 6 of New York, have invented certain new and useful Improvements in Levels, of which the following is a specification.

My invention relates to levels and particularly contemplates the provision of an 10 improved structure of this character especially designed for use in conjunction with boring braces, though detachable therefrom for use in conjunction with a square, rule, or like implement.

15 My invention further and specifically resides in the following features of construction, arrangement and operation as will be hereinafter described with reference to the accompanying drawings forming a part of 20 this specification, in which like numerals are used to designate like parts throughout the several figures, and in which,

Figure 1 is an elevation of a boring brace illustrating my improvements attached there- 25 to and in the extended position, Fig. 2 is a horizontal sectional view taken on the line 2--2 of Fig. 1, Fig. 3 is a vertical sectional view taken through my improvements in a closed position. Fig. 4 is an enlarged sec- 30 tional view on the line 4--4 of Fig. 2, and broken away, Fig. 5 is an elevation of a portion of the device and to be hereinafter specifically referred to, Fig. 6 is a plan view of the sliding indicator, Fig. 7 is a face view 35 of a portion of the square or rule and showing the level attached thereto, and Fig. 8 is a section through said rule or square and illustrating the same.

In the practical embodiment of my invention, I provide the handle portion A of a 40 boring brace B with a rectangular casing 1 mounted thereabout, and having secured therein a skeleton frame 2. The frame 2 is preferably arranged independent of the cir- 45 cular movement of the operating parts of the brace B, by fitting the same upon flattened portions of the handle A which is in the form of a sleeve fitting loosely about the upper portion of the brace B.

50 My improved level comprises rectangular skeleton frames 2, 3 and 4, each of said sec- tions 2 and 4 being provided with longitudinal slots 5 having beveled edges 6 sliding upon the double beveled longitudinal edges 55 7 of the central sections 3, by this means the said frames or sections 2, 3 and 4 may be

telescoped one upon the other to occupy the closed position within the casing 1 or to be extended outwardly as shown in Fig. 1 in order that the operator of the brace be made 60 positive that the tool is exactly perpendicular before beginning to bore. For this purpose the outer section or frame 4 is provided with horizontal levels 8 upon its side and front pieces and with a vertical level 9 65 upon its front face. Thus the operator of the brace B may be sure that the tool is exactly at right angles to the work, and in order to render the levels accurate and operable to angular work, I provide the levels 8 70 and 9 each with a sliding indicator 10 mounted through a slot 11 adjacent the level and provided with an upwardly extending edge 12 engaging with a flange 13 to prevent the accidental removal of said indicator and to 75 hold the same slidably within the slot 11. The indicators 10 are further provided with an indicator finger 14 extending above the level and adapted to be moved to different points thereon when an angular opening is 80 desired to be bored, said indicators being held stationary when desired by a small set screw 15 threadedly engaging through an opening in said indicator and adapted to engage the material of the level housing. 85

In order that the extensible frames or casings 2, 3 and 4 may not be pulled entirely apart, I provide the inner and outer sections 2 and 4 with longitudinal slots 16 and I provide the central frame or section 3 with 90 studs 17 screwed thereon and projecting within said slots 16.

In case it may be desired to use my improved level in conjunction with a square, rule, or the like C, I may provide the outer 95 section 4 with a pair of curved spring fingers 18 extending therefrom and adapted to be clasped over the square or rule C as shown in Figs. 7 and 8.

Having thus fully described my invention, I claim:

1. In a device of the character described, the combination with a boring brace or the like, of an extensible series of frames or sections mounted thereon, and levels carried 105 by the outer one of said sections, substantially as described.

2. In a device of the character described, the combination with a boring brace or the like, of a plurality of frames or sections nor- 110 mally held adjacent and mounted about said brace and having sliding connections with

one another, and levels carried by one of said sections, substantially as described.

3. In a device of the character described, the combination with a boring brace, of a 5 casing carried thereby, a plurality of frames or sections normally carried within the casing and having sliding connections with one another and levels carried by one of said sections, substantially as described.

10 4. In a device of the character described, the combination with a boring brace, of a plurality of frames or sections having sliding connections with each other and normally held adjacent and mounted about said 15 brace and adapted to be extended at right angles thereto, and levels carried by one of said sections, substantially as described.

5. In a device of the character described,

the combination with a boring brace, of a plurality of frames or sections normally held adjacent and mounted about said brace, said sections having sliding connections with each other and being arranged to extend outwardly at right angles to said brace and detachable from one another, and levels carried by one of said frames or sections, said last named section being provided with curved spring fingers adapted for engagement with a square, rule or like implement, substantially as described.

20 25 30 In testimony whereof I affix my signature in presence of two witnesses.

FERDINAND SCHTABE.
